UNITED STATES PATENT OFFICE.

EDWIN B. STIMPSON, OF BROOKLYN, NEW YORK.

DESIGN FOR A STRAP.

SPECIFICATION forming part of Design No. 19,290, dated August 27, 1889.

Application filed August 5, 1889. Serial No. 319,836. Term of patent 7 years.

To all whom it may concern:

Be it known that I, EDWIN B. STIMPSON, of Brooklyn, in the county of Kings and State of New York, have invented and produced a 5 new and useful Design for Straps, of which the following is a specification.

The accompanying drawing illustrates a strap embodying my design.

The design consists, essentially, of straight 10 parallel lines A at the outer edges of the strap. Inward of the straight parallel lines A are rows B of scallops. These scallops are curved throughout. To the rear of each of the

scallops is a dot or circle a. Inward of the dots or circles a are rows b, having the appearance of stitching. Inward of the rows b are rows of dots or circles C.

What I claim as my invention, and desire to secure by Letters Patent, is—

The design for a strap, substantially as 20 herein shown and set forth.

EDWIN B. STIMPSON.
